HIGH VOLTAGE MERCURY ARRESTER

Application filed May 17, 1930, Serial No. 453,285, and in Japan May 22, 1929.

The present invention relates to lightning arresters, and particularly to those of the mercury-arc type.

The chief object of the invention is to provide a compacted and simplified, yet exceedingly high-capacity lightning arrester adapted to function with any voltage. It is peculiarly well fitted for high-voltage and high-discharge devices in which the voltage has a tendency to drop suddenly.

My improved device is shown in the accompanying drawing, in which

Fig. 1 is a composite view, part (a) showing one of the elements in top plan, part (b) showing this element in longitudinal cross-section, and part (c) being a bottom view.

Fig. 2 is a central longitudinal section showing two of the discs of Fig. 1 assembled to form the complete device.

The present invention consists essentially of a pile of discs for generating in vacuo, a plurality of mercury arcs in series. The discs are so shaped as to cause the mercury arcs to arise in series steps in each disc and to zigzag between adjacent discs. The construction and operation are very simple, but the pile has greater capacity than corresponding types.

As shown in the drawing the discs are made of some insulating material such as glass or porcelain, and in these discs 1, 2, 3 are mercury pools; 4, 5 are damming walls therefor; 6, 7, 8 are walls projecting from the back to form intercepting walls fitting into the mercury pools; and 9 is a hole for causing the mercury arcs to zigzag between discs, and also serves as an outlet for mercury. The height of the damming walls varies down gradually from the outermost to the innermost, so that the mercury pools stand in downwardly sloping steps when the disc is filled with mercury. As shown in Fig. 2, when a plurality of individual discs made as in Fig. 1 are piled up opposite-ended, the hole 9 of one comes over the mercury pool 1 of the next lower disc, and the intercepting walls 7 and 8 come in the middle of the mercury pools 2 and 3 of the lower disc, touching the surface of the mercury.

When voltage is impressed on the device, a

plurality of mercury arcs arise step by step on each disc, and then passes between the discs in a zigzag form. First the arc passes to the right, in Fig. 2, from the surface of mercury pool 1 over wall 4, and flashes to the surface of pool 2. From the pool it passes over the wall 5 from the surface of 2, to pool 3, and then from pool 3 to the mercury pool 1 of the next disc, passing thither through the hole 9, and so on, establishing and completing the discharge-path. In this way, the lightning-discharge is accommodated and the lightning-discharge voltage becoming weaker and weaker until finally the lightning is dissipated.

By piling up a number of the present discs alternately one upon another, as shown in Fig. 2, and enclosing them in such a manner as to form a simple vacuum chamber, or by initially casting or otherwise forming them integral so as to form a vacuum-cylinder, the present arrester devices, though giving rise to a multiplicity of mercury arcs in small compass and in series, can be cheaply manufactured on a large scale by a considerably simplified process, yet provide an arrester which has great discharge capacity and is applicable to any high voltage.

Having thus described my invention what I claim is:

1. A mercury-arc arrester, comprising a plurality of superimposed disc-like mercury-containers, and means therein for causing the discharge arc to pass along each separate, component disc in a series of steps and to pass from disc to disc in zigzag form.

2. In a mercury-arc arrester of the class described, a mercury-containing disc having a plurality of concentric damming walls on one face, a plurality of concentric intercepting walls projecting from the opposite face, and an aperture through the center of the concentric intercepting walls.
